GEORGE KEITH, OF LONDON, ENGLAND, ASSIGNOR OF ONE-HALF TO JAMES KEITH, OF LONDON, ENGLAND.

GAS-LAMP.

1,100,434.

Specification of Letters Patent. Patented June 16, 1914.

Application filed November 3, 1913. Serial No. 798,939.

To all whom it may concern:

Be it known that I, GEORGE KEITH, a subject of the King of the United Kingdom of Great Britain and Ireland, and residing at 5 London, England, have invented a certain new and useful Improvement in Gas-Lamps, of which the following is a specification.

This invention relates to inverted incandescent gas lamps and has for its primary 10 objects to afford increased protection against overheating of the burner nozzle and also to provide a simplified arrangement for carrying the mantle.

In the specification of Letters Patent No. 15 917876 there is described a high pressure inverted incandescent gas lamp provided with a gas and air heater to which is fitted a nozzle of substantial cross section and composed 20 of good conducting metal on which is closely fitted a non-conducting ring serving to support the mantle.

In accordance with the present invention the ring is spaced from the nozzle, *e. g.*, is enlarged internally as well as externally, 25 and supported from the underside of the heater, provision being made to prevent circulation of the burnt gases through the space thus formed between the ring and the nozzle.

Figure 1 of the accompanying drawing is 30 a longitudinal vertical section of a gas lamp embodying the invention; Fig. 2 is a detail view to a larger scale.

Referring to the drawing, 1 denotes the nozzle of good conducting metal and substantial cross section located at the mouth 35 of, and in thermal contact with, the gas and air heater 2; the said nozzle being preferably of substantially hemispherical form to insure adequate conduction of heat from the tip. A ring 3 of non-conducting material which desirably conforms in shape with the nozzle *e. g.*, is shaped as a cup having a central aperture, is supported from the heater 2 by a screw-threaded connection or the like, 40 so as to afford between its inner wall and the outer wall of said nozzle a substantially annular space 4 closed at its upper end. With this construction the lower portion of the heater 2 is protected against overheating—a 45 matter of importance by reason that an important function of the lower portion of the

heater is to extract heat from the nozzle. The ring 3 is preferably formed with an annular recess 5 adjacent to the boundary of the aperture.

55

The soft mantle 6, instead of being supplied with a non-conducting ring, as usual, is fitted with a light ring 7, preferably of suitable wire, sewn or attached to the upper end of the mantle fabric, the diameter of 60 said ring 7 exceeding the diameter of the aperture in the ring 3.

To attach the mantle 6, it suffices to unscrew the ring 3 from the heater 2, and drop the fabric through the aperture in said ring 65 from above, the ring 7 being allowed to rest in the recess 5, the mantle being then formed and shaped in the usual way, and the ring 3 replaced.

Apart from economical considerations involved in the substitution of a light ring for the usual non-conducting mantle ring, the mantle suspension above described presents the advantage that in the selection of a mantle the user is not limited to the employment 75 of mantles having a diameter at the upper end exceeding that of the bore of the nozzle, but may employ a mantle of any practicable diameter. The top of the mantle being exposed directly to the flame is 80 hardened more satisfactorily than it is in the case where it is fixed on the outside of an ordinary mantle ring and so shielded from the flame. With the present arrangement, therefore, the use of a hardening liquid may 85 be dispensed with.

I claim:

1. In an inverted incandescent gas lamp, in combination, a gas and air heater, a metallic nozzle of substantially hemi-spherical form in thermal contact with said heater, and a cup-shaped mantle-supporting ring of non-conducting material, the lower extremity of said ring extending below the lower end of said nozzle, said ring being fitted to 90 said heater and affording between its inner wall and the outer wall of said nozzle a space closed at its upper end.

2. In an inverted incandescent gas lamp, in combination, a heater, a nozzle in thermal 100 contact with said heater and a mantle-supporting ring fitted to said heater and par-

tially inclosing said nozzle, the lower extremity of said ring extending below the lower end of said nozzle, said ring being in the form of a cup having at its lower end a central aperture provided in its interior face with an annular recess adjacent to the boundary of said aperture.

In testimony whereof I have signed my name to this specification in the presence of two subscribing witnesses.

GEORGE KEITH.
